MAGNETIC SOUND RECORDING DEVICE

Arnold Stapelfeldt, Berlin, Germany, assignor to
 C. Lorenz Aktiengesellschaft, Berlin-Tempelhof, Germany, a company

Application June 7, 1939, Serial No. 277,780
 In Germany June 14, 1938

10 Claims.

(Cl. 274—1)

Magnetic recording devices of the type designated as "steeltone" machines are known which comprise a machine wherein recordings are made magnetically on a steel tape or wire and include a mechanism coupled with the motor drive and having a hand or pointer for indicating the length of that part of the wire- or tape-shaped record carrier which at the time is available for recording. Also switching means have been provided which act to stop the machine after a predetermined part of the record carrier has been uncoiled. In most of the latter cases indicating devices of the type having rotary pointers are employed. Furthermore, scales have been used which have a nut screw in engagement with a spindle or lead screw and arranged to move along this spindle under the influence of a guide rod for such nut. This rod is mounted on a casing in which the well-known bobbins or reels are contained, and is displaceable in its longitudinal direction. When now the nut comes against an adjusting ring the guide rod is displaced and thereby acts to stop the machine. This arrangement has the disadvantage that the machine will be stopped by every impact influencing it and will be stopped also whenever the guide rod is touched.

In accordance with the invention it is proposed to render the spindle displaceable along its axis and to effect the stoppage of the machine by means of electric contacts controlled by the spindle. In this way any accidental stoppage of the machine will be obviated, as all of the movable members are mounted in the reel casing and as in addition these members are prevented by suitable holding means from being displaced under the influence of shocks.

The invention will be understood from the following description, reference being had to the accompanying drawing in which

Fig. 1 is a fragmentary longitudinal sectional view illustrating one embodiment of the invention. Fig. 1a shows a fragmentary cross section of this embodiment along the section line A—A. Fig. 1b is a fragmentary top plan view of the structure shown in Fig. 1. Fig. 2 is a longitudinal sectional view representing a modification of the arrangement shown in Fig. 1. Fig. 3 is a fragmentary sectional view illustrating a modification of a detail of the construction represented in Fig. 2. Fig. 4 is a view similar to Fig. 3 and shows a second modification of such detail.

Q denotes a casing in which the well-known reels, not represented in the drawing, are located. Within this casing also a lead screw or

spindle 1 is arranged. This spindle is mounted in supports T, fixed within the casing Q, and is revoluble and axially displaceable in these supports. Secured to spindle 1 at the bearing ends 5 so as to be displaced longitudinally with the spindle is a slide 2 so as to move longitudinally therewith. A pair of bevel wheels G serve to drive the spindle 1 from a motor M, namely, the motor employed to drive the said reels. Spindle 1 is in engagement with a nut 3 provided with an extension Z that projects into a longitudinal slot of a scale S. In this way, whenever spindle 1 is rotating, nut 3 will move along it. The guide extension Z also is the pointer for scale S. The nut 3 carries a trunnion formed with an arm 4 and is on either side of this arm provided with a shoulder or stop b therefor, so that the arm 4 can be rotated through a certain angle and in a plane parallel to the spindle 1. Scale S has a series of holes L spaced apart at distances by which predetermined periods of operation of the machine are defined, such as one-minute periods, for instance. These holes are adapted to receive a pin 5 to be inserted in one or another of the holes in order to strike against arm 4 and thereby to stop the nut 3 in its movement along spindle 1. The shoulders b are arranged to arrest arm 4 when the nut 3 is in the mid-position with respect to the pin 5, no matter in which direction the nut is travelling. As soon as nut 3 is stopped in this way the spindle 1 owing to its continued rotation will be axially displaced in the direction opposite to the direction in which the nut 3 has travelled. Slide 2, being secured to spindle 1, shares in any axial movement the spindle is subjected to. The slide 2 carries a stud 6 in engagement with a lever 7. Two sets of contact springs F tend to hold the lever 7 in the mid-position represented in Fig. 1 and thus also tend to hold the slide 2 and spindle 1 in the mid-position. Whenever now the nut 3, travelling along spindle 1 in one direction or the other, is stopped by the pin 5 inserted in one of the holes L, spindle 1 is longitudinally displaced in the direction opposite to that in which the nut has been moved, and thereby with the aid of slide 2 acts to deflect lever 7. This lever consequently closes one or the other of the contacts formed by the springs F and in this way acts to stop the machine. A movable pin 8 serves to actuate a contact 9 and thereby to produce a signal in order to indicate that the record carrier will soon have finished its travel. Pin 8 is acted upon by nut 3, which for this purpose is

milled at its lower end to present bevel surfaces 10, as shown. The advantage of this construction is especially that the duration of recording and hence the length of that part of the wire- or tape-shaped record carrier which is to be re-coiled is adjustable at will and also, that the component parts of the machine need not be snugly fitted together.

As shown in Fig. 2, instead of the holes L, Fig. 1, a slot C may be provided in the casing Q. In this case screws or springs may serve to fix the pin 5 in the desired position in slot C. For instance, the pin 5 shown in Fig. 2 has a clasp nut D screwed upon it, and is provided inside with a stop A. Nut D is serrated or may be a thumb screw.

In the construction represented in Fig. 3 the pin 5 is clamped fast by a leaf spring BF arranged between the stop A of this pin and the upper wall of the casing Q.

Fig. 4 shows a spiral spring SF provided in lieu of this spring BF as shown in Figure 3.

What is claimed is:

1. In a sound recording device, a frame, a drive means, a rectilinear scale, a spindle rotatable under control of said drive means and displaceable along its axis, a pointer cooperating with said scale to give an indication, adjustable stop means, means carrying said pointer and engaging said spindle and movable along said spindle under control of rotation thereof into contact with said stop means, and switch means for stopping said motor, said switch means being operated as said carried means contacts said stop means.

2. A device according to claim 1, in which the said spindle is a lead screw and in which the said adjustable stop means comprises a stop pin, said scale being provided with a series of holes adapted to receive such stop pin, and in which said means carried by said spindle comprises a nut in engagement with such lead screw and adapted to come against said stop pin.

3. A device according to claim 1, in which the said spindle is a lead screw and in which the said adjustable stop means comprises a stop pin, said scale being provided with a series of holes

adapted to receive such stop pin, said means carried by said spindle comprising a nut in engagement with such lead screw and adapted to come against said stop pin, this nut carrying a lever for the stop pins to strike against, and stops for such lever formed on said nut to arrest the said nut in its mid-position with respect to the stop pin.

4. A device according to claim 1, further comprising a slide fastened to the said spindle, and an electric contact device operated by said slide for stopping said drive means.

5. A device according to claim 1, further comprising a slide rigidly secured to the said spindle, an electric contact device for stopping said drive means, and a lever for actuating such contact device, this lever being engaged by said slide.

6. A device according to claim 1, in which said adjustable stop means includes a stop pin adjustably securable in a longitudinal slot in said frame.

7. A device according to claim 1, in which said adjustable stop means includes a stop pin adjustably securable in a longitudinal slot in said frame, and means, comprising a clasp nut, for fixing this pin in such slot.

8. A device according to claim 1, in which said adjustable stop means includes a stop pin adjustably securable in a longitudinal slot in said frame, and means, comprising a clasp nut at one end of the pin and spring means at the other end thereof, for fixing this pin in said slot.

9. A device according to claim 1, in which said adjustable stop means includes a stop pin adjustably securable in a longitudinal slot in said frame, and means, comprising a clasp nut at one end of the pin and a leaf spring at the other end thereof, for fixing this pin in said slot.

10. A device according to claim 1, in which said adjustable stop means includes a stop pin adjustably securable in a longitudinal slot in said frame, and means, comprising a clasp nut at one end of the pin and a helical spring at the other end thereof, for fixing this pin in said slot.
